E. MATSON.
COMBINATION SAW.
APPLICATION FILED NOV. 11, 1912.

Patented Aug. 25, 1914.

UNITED STATES PATENT OFFICE.

ERIC MATSON, OF MILLER, INDIANA.

COMBINATION-SAW.

1,108,382.

Specification of Letters Patent. Patented Aug. 25, 1914.

Application filed November 11, 1912. Serial No. 730,763.

To all whom it may concern:

Be it known that I, ERIC MATSON, a citizen of the United States, residing at Miller, in the county of Lake and State of Indiana, have invented certain new and useful Improvements in Combination-Saws; and I do declare the following to be a full, clear, and exact description of the invention, such as will enable others skilled in the art to 10 which it appertains to make and use the same.

This invention relates to improvements in combination saws.

One object of the invention is to provide 15 a saw having a series of bits provided with different sizes and styles of teeth and adapted to be independently connected with the blade of the saw thereby converting the same into a fine or coarse, rip or cross cut saw.

Another object is to provide a saw of this 20 character which will be simple, strong, durable and inexpensive in construction, efficient and reliable in operation and which may be 25 quickly and easily converted from one style of saw to another.

With these and other objects in view the 30 invention consists of certain novel features of construction, and the combination and arrangement of parts as will be more fully described and claimed.

In the accompanying drawings: Figure 1 is a side view of my improved saw; Fig. 2 is an enlarged cross sectional view of the 35 same; Fig. 3 is an enlarged side view partly in section of the outer end of the saw blade and one of the bits attached thereto showing more clearly the manner of fastening the outer end of the bit to the saw blade; Fig. 40 4 is an enlarged detail vertical section of the rear end of the saw blade taken on the line 4-4 of Fig. 1; Fig. 5 is a detail sectional view of the rear end of the blade taken on the line 5-5 of Fig. 1; Fig. 6 is a 45 detail perspective view of one of the saw bits removed from the blade; Fig. 7 is a detail perspective view of the bit fastening member for the rear end of the bit; Figs. 8 and 9 are detail side views of parts of 50 other styles of bits which may be employed in connection with my improved saw.

Referring more particularly to the drawings, 1 denotes my improved saw which comprises a blade 2 of any suitable size and 55 width to the inner end of which is secured a handle 3 by screws 4 or similar fastening

devices. In the lower edge of the blade 2 is formed a longitudinal groove or channel 5 and in the outer end thereof and intersecting the groove 5 is a transverse locking 60 pin 6.

Adapted to be engaged with the groove or channel 5 in the lower edge of the blade 2 are saw bits 7 of which any desired number may be provided having different sizes 65 or styles of teeth. The bits 7 are preferably in the form of narrow bars on the outer edges of which are formed the saw teeth 8 while on the inner or upper edges thereof are formed longitudinal tongues 9 which are adapted to fit into the groove 5. At the outer end of each of the bits the tongue 9 has formed thereon an upwardly projecting hook 10 which is adapted to be engaged with the locking pin 6 thereby securely fastening 75 this end of the bit in place.

In the tongue 9 of each of the bits near the inner end thereof is a transverse aperture 11 which when the bit is in place is brought into alignment with similar apertures 12 formed in the opposite sides of the grooved lower edge of the blade. With the apertures 11 and 12 is adapted to be engaged a stud 13 formed on and projecting laterally from the lower arm 14 of a bit fastening 80 clasp 15 which has a U-shaped body 16 adapted to fit in recesses 17 formed in the 85 opposite sides of the rear end of the blade and to grip the edge of this end of the blade as shown in Fig. 5.

The numeral 18 designates the upper arm having at its upper end an inwardly projecting hook whose bill 20 is adapted to engage a locking aperture 21 formed in the 90 saw blade whereby this end of the arm 18 95 and the entire clasp are held in place.

The clasp 15 is formed of spring metal and the arms 14 and 18 diverge from the body and are adapted to be sprung into engagement with recesses 22 and 23 which 100 are provided to receive said arms whereby when the clasp is in position it will lie flush with the adjacent surfaces of the blade while the stud and hook will engage their respective apertures for holding the clasp in place 105 and for fastening the inner end of the bit to the lower edge of the blade. In applying the clasp, the arm 14 is engaged with the recess 22 and the stud 12 thereon engaged with the apertures in the saw blade and in 110 the tongue of the bit, after which the blade gripping portion of the clasp and the arm

18 are sprung into engagement with their respective recesses and the hook 19 into engagement with the aperture 21 thereby securely fastening the clasp to the saw blade 5 for holding the inner end of the bit in place.

By constructing and arranging my improved saw and the bits thereof as herein shown and described and providing a number of different styles of bits it will be seen 10 that the latter may be readily interchanged and securely fastened in operative engagement with the saw blade thus converting the latter into a fine or coarse, rip or cross cut saw as desired.

15 From the foregoing description taken in connection with the accompanying drawings, the construction and operation of the invention will be readily understood without requiring a more extended explanation.

20 Various changes in the form, proportion and the minor details of construction may be resorted to without departing from the principle or sacrificing any of the advantages of the invention as claimed.

25 Having thus described my invention, what I claim is:

1: A saw blade having a grooved lower edge with a pin across the outer end of the groove and apertures in the side walls of the 30 groove near its inner end; combined with a bit having a tongue to fit said groove, and the tongue having a hook at its outer end to engage the pin and an aperture through its inner end to register with those in said wall, 35 and a clasp movably sprung onto the rear end of the saw blade and having a stud passing through the alined apertures.

2: A saw blade having a grooved lower edge with a pin across the outer end of the 40 groove and apertures in the side walls of the groove near its inner end; combined with a bit having a tongue to fit said groove, the tongue having a hook at its outer end to engage the pin and an aperture through its 45 inner end to register with those in said wall, and a clasp movably sprung onto the rear end of the saw blade and having a depending arm provided with an inturned stud to engage the alined apertures and an upper arm 50 with means for fastening it to the saw blade.

3: A saw blade having a grooved lower edge with a pin across the outer end of the groove and apertures in the side walls of the groove near its inner end; combined with a 55 bit having a tongue to fit said groove, the tongue having a hook at its outer end to engage the pin and an aperture through its inner end to register with those in said wall, a clasp having a U-shaped body adapted to

be sprung onto the rear end of the saw blade, 60 the latter having an aperture near its upper edge, an arm depending from said clasp-body and carrying a stud engaging the alined apertures, and a second arm rising from said U-shaped body and provided with 65 a hook adapted to engage the aperture in the blade.

4. The combination with a saw blade having an aperture through it near its lower edge and at its inner end, a bit fitting said 70 edge and pierced with an aperture adapted to register with that in the blade, and connections between the outer ends of the blade and bit; of a clasp whose body is adapted to embrace the rear end of the saw blade, the 75 latter being provided with recesses in its opposite faces to receive the clasp, and an arm depending from the latter and having a stud engaging the alined apertures.

5. The combination with a saw blade having an aperture through it near its lower edge and at its inner end, a bit fitting said 80 edge and pierced with an aperture adapted to register with that in the blade, and connections between the outer ends of the blade 85 and bit; of a clasp having a U-shaped body adapted to embrace the rear end of the saw blade, and upwardly and downwardly extending arms, the latter having a stud adapted to enter the alined apertures, the 90 blade being provided with recesses to receive said body and arms whereby they will lie flush with its faces, and means for detachably securing the upper arm to the blade.

6. The combination with a saw blade having an aperture through it near its lower edge and at its inner end, a bit fitting said 95 edge and pierced with an aperture adapted to register with that in the blade, and connections between the outer ends of the blade 100 and bit; of a clasp having a U-shaped body adapted to embrace the rear end of the saw blade, and upwardly and downwardly extending arms, a stud on the lower arm projecting through the alined apertures, and an 105 inturned hook at the extremity of the upper arm, the faces of the saw blade having recesses to receive said clasp and its arms whereby they lie flush with said faces and the body of the saw blade having an aperture to receive said hook.

In testimony whereof I have hereunto set my hand in presence of two subscribing witnesses.

ERIC MATSON.
